UNITED STATES PATENT OFFICE

2,558,898

TABERNACLE

James F. Campbell, Milton, Mass.

Application November 30, 1946, Serial No. 713,305

1 Claim. (Cl. 312—33)

1

The present invention comprises a new and improved tabernacle for use on the table of the altar for holding the chalice between services.

It is most important that such appurtenances of the service be securely and completely protected from tampering, fire or theft, and at the same time that the tabernacle in which they are placed should be appropriate in its appearance upon the altar and convenient in its construction for the priest. The tabernacle of my invention combines these characteristics in that its general design conforms to ecclesiastical lines, its capacity is ample, provides maximum protection against fire and theft by including an automatic locking device, and it is particularly convenient in operation in that it includes a single key-operated mechanism for both unlocking the door and moving it to open position.

An important feature in bringing about the desired results resides in a key-operated actuating element having direct connection for releasing the lock and a delayed action connection for moving the door so related and timed that the door is first released from its locked condition and then, at the same continuous movement of the actuating element, the door is moved to its wide open position. Conversely, when the door is closed by reverse action of the actuating element, it is automatically locked in its closed position without further attention.

These and other features of the invention will be best understood and appreciated from the following description of a preferred embodiment thereof, selected for purposes of illustration and shown in the accompanying drawings, in which:

Fig. 1 is a view of the tabernacle in front elevation,

Fig. 2 is a fragmentary view in longitudinal section of the locking mechanism,

Fig. 3 is a plan view of the tabernacle as seen from beneath,

Fig. 4 is a fragmentary view in perspective and on an enlarged scale of the curtain supporting means,

Fig. 5 is a view of the base in cross-section and on an enlarged scale, and

Fig. 6 is a view in cross-section on the line 6—6 of Fig. 1 but on an enlarged scale.

In its illustrative embodiment the tabernacle comprises a hollow circular base 10 upon which is supported an upright cylindrical body 11 having a flanged circular top 12 from which arises appropriate ornamental insignia 13. The cylindrical body 11 is provided with an opening defined by a rectangular door frame 14 and is sup-

plemented by three spaced interior cylindrical shells or partitions 15 which not only stiffen the structure of the tabernacle as a whole, but provide enclosed air spaces which are efficient as insulation to protect the contents of the tabernacle in case of fire.

Within the partitions 15 of the cylindrical body is provided a rotary cylindrical door 16 having a flat circular bottom 17. The door itself carries a frame 18 which fits the frame 14 when the door is in closed position as shown in Fig. 6. The door carries in its rear side a vertical bar 19 which cooperates with the lock as will be presently described. The door carries an ornamental panel which is exposed when the door is in closed position as shown in Fig. 6, whereas a 45° rotation of the door in counter-clockwise direction will open the tabernacle for the full width of the frame 14.

The base 10 is closed by a circular horizontal partition 20 to the upper face of which is secured a circular plate 21 having a ball race in its upper surface. To the bottom 17 of the door is secured a similar circular plate 22 having a corresponding ball race for the ball bearings 23 which thus support the rotary door and facilitate its movement to and from closing position. A short vertical shaft 24 projects downwardly from the bottom 17 of the door through the partition 20 and into the base where it is provided with a bevel gear 25. The bevel gear 25 meshes with a corresponding bevel gear 27 fast to the inner end of a horizontal shaft 26 journaled in bearing brackets 28 which extend downwardly from the partition 20 as best shown in Fig. 3. A lock 29 is set in the front wall of the base 10 and surrounds the forward end of the shaft 26. A key 30 is provided for this lock and has the double function of releasing the cylindrical door for movement and of actuating it in its opening and closing movement.

A vertically movable bolt 31 is provided for engaging the bar 19 of the door and positively locking the door in its closed position. The bolt 31 is mounted for movement in a stationary sleeve 32 fast to the partition 20. The bolt has at its lower end a transversely extending head 33 and this is connected through a tension spring 34 to a pin extending transversely through the sleeve 32 and the bolt 31 which is slotted so that it may move freely with respect to the pin. The upper end of the bolt is beveled so that the bolt may be depressed by contact with the lower end of the bar 19 when the latter is moved over it in closing the door.

As shown in Fig. 5, the head 33 is engaged by the free end of a lever 35 pivotally supported by a pin 36 mounted beneath the partition 20 and extends into the vicinity of the lock 29 where it is provided with a latch piece 37 controlled by a tension spring 38.

The lock is encircled by a sleeve 39 connected to a lifting cam 40 upon which the latch 37 normally rests. The sleeve 39 includes a loop-shaped portion in which is located an arm 41 fast upon the shaft 26. When the key 30 is inserted in the lock it first rocks the sleeve 39 lifting the cam 40 and depressing the free end of the lever 35, thus forcing the bolt 31 downwardly and releasing the cylindrical cover 16. In the continued rotation of the key, the loop-shaped portion of the sleeve 39 engages the arm 41 on the shaft 26, turning the shaft and through the bevel gears 27 and 25 rotating the door to its open position. In this movement the latch 37 is temporarily displaced to permit the lifting cam 40 to pass it and these parts are restored to their initial position as shown in Fig. 5 when the door is again closed.

The flanged top 12 of the tabernacle contains and conceals a tubular slotted ring 42 in which is contained a number of ball-headed hooks 43 from which are suspended a curtain 44 of ornamental fabric. This mounting for the curtain permits it to be readily drawn from open position, as shown in Fig. 1, to closed position should that be desired.

Having thus disclosed my invention and de-

scribed in detail an illustrative embodiment thereof, I claim as new and desire to secure by Letters Patent:

A tabernacle safe comprising stationary concentric shells spaced to provide intermediate air spaces and having a front opening, a stationary bottom plate, a circular plate rotatably mounted thereon, an arcuate door carried by said rotatable plate and shaped to close said front opening, a vertical bar movable with the rotary plate and located at the rear side of the safe when the door is closed, a latch carried by the stationary bottom plate and movable to engage said bar for locking the door, a lever pivotally mounted on the under side of the bottom plate and engaged with the latch, and key operated mechanism for rocking said lever and for moving the said door.

JAMES F. CAMPBELL.
